UNITED STATES PATENT OFFICE.

AMELIA BAILLIE, OF NEW YORK, N. Y., ASSIGNOR TO NATHAN KRAUSKOFF CO., OF NEW YORK, N. Y., A CORPORATION OF NEW YORK.

GARMENT.

1,411,601.

Specification of Letters Patent. Patented Apr. 4, 1922.

Application filed December 14, 1921. Serial No. 522,215.

To all whom it may concern:

Be it known that I, AMELIA BAILLIE, a subject of the King of Great Britain, and resident of the borough and county of the Bronx, city and State of New York, have invented certain new and useful Improvements in Garments, of which the following is a specification.

My invention relates to garments and more particularly to garments for children and has for its object to provide a combination garment constructed in a novel manner and so as to be capable of being easily and quickly adjusted from the form in which it is worn to a dismantled flat condition to facilitate laundering, storing and packing thereof. Other more specific objects will appear from the description hereinafter and the features of novelty will be pointed out in the appended claims.

In the accompanying drawings, which, without defining the limits of the invention, illustrate an example thereof in the form of a child's garment of the type commonly known as a bloomer dress, Figure 1 is a perspective view of the garment as it appears when worn; Fig. 2 is an inside face view showing the garment partly dismantled; Fig. 3 is an outside face view of the garment in its completely dismantled condition, and Fig. 4 is a similar view from the inside.

The garment shown in the drawings, which is intended to be illustrative of the invention, comprises a dress 10 consisting of a rear panel 11 and a front panel 12 cut out at 13 to form a neck opening of the desired shape and dimensions; the panels 11 and 12 are adapted to be folded upon themselves along a shoulder line 14 to form the front and back of the dress and are provided with lateral extensions 15 arranged to form the sleeves of the garment. Any suitable means may be included for detachably connecting the front and rear panels to maintain the dress in the form in which it is intended to be worn; for instance, co-operating fastening devices 16 and 17 of the glove fastener type may be secured upon the panels 11 and 12 in a manner to co-operate with each other. These devices 16 and 17 may be located in any predetermined manner to secure the desired effect in the dress; for instance, as shown, said devices 55 may be positioned approximately at the

points at which the extensions 15 merge into the respective panels 11 and 12. With this arrangement, when the garment is worn, the dress will be slitted along its opposite sides in the desired fashionable manner 60 which, at the present time, is popular for bloomer dresses; it will, of course, be understood that the number of devices 16 and 17 may be increased and their locations varied to provide different dress arrangements. In 65 the preferred form the panels 11 and 12 are hemmed along their free edges, as indicated at 11^a and 12^a respectively.

In the illustrated example, the garment includes bloomers 18, consisting of a front 70 section 19 and a rear section 20 adapted to fold upon themselves along a line 21 and which are cut inwardly along converging lines 22 and 23 to form recesses which constitute the leg openings 24 when the garment is in its assembled condition. The bloomer sections 19 and 20, which are integral continuations of each other, are preferably attached, through the medium of the front bloomer section 19, upon the inside 80 of the front panel 12 at a distance from its free edge and preferably adjacent to the inner edge of the hem 12^a, as shown in Fig. 4. The sections 19 and 20 are detachably connected with each other along their side 85 edges by means of co-operating fastening devices 25 and 26 and may further be provided with ribbons 27 adapted to be tied together in the form of bows at the outside lower edges of the leg openings 24, as shown 90 in Figs. 1 and 2. In addition, the free edge of the rear section 20 may be provided with a band 28 to which fastening devices in the form of buttons 29 may be sewed; the latter or their equivalents are intended for 95 connection with buttonholes 30 or equivalent devices located upon tabs 31 sewed to or forming integral parts of the front panel 12, as shown in Figs. 3 and 4. The devices 29 and 30 co-operate to maintain the rear 100 section 20 of the bloomers in its closed position; the band 28 may further be provided with one or more buttonholes 32 adapted for connection with the usual waist band customarily worn by children at this 105 time. The garment may further include any other features customarily formed in garments of the type in question as, for instance, a belt 33 held in belt loops 34 located upon the rear panel 11; furthermore, any 110

- desired ornamentation or special features may be included in the garment, as indicated by way of example at 35 in Fig. 1. In addition, the garment may include a front slit 5 36 normally closed by means of fastening devices 37 adapted to be disconnected to permit the garment to be easily put on and taken off.
- In practice, the panels 11 and 12 are 10 folded upon each other on the shoulder line 14 and the fastening devices 16 and 17 are connected whereby said panels and the lateral extensions 15 are fixed in registry with each other to form the dress and its 15 sleeves, the dress, as before stated, being slitted along its opposite sides. Either previously or at this stage, the rear section 20 of the bloomers 18 is folded upon the line 21 to bring the side edges of said section 20 into juxtaposition to the corresponding edges of the section 19 and the fastening devices 25 and 26 are connected to maintain said sections in the form of bloomers, as shown; the ribbons 27 may now be tied in 25 the form of bows to complete the leg openings 24 and at the same time to ornament the garment. After the latter is in place upon the child the buttons 29 may be connected with the buttonholes 30 of the tabs 30 31 to maintain the rear section 20 in a closed position; by simply disconnecting the buttons 29 from the buttonholes 30, the rear section 20 may be turned down to an open position whenever, for any reason, this is 35 required, this adjustment of said section 20 being easily possible while the garment is worn and requiring no special manipulation of the latter. In its assembled condition the garment may be easily put on and taken off 40 40 by simply disconnecting the fastening devices 37 and 29 and 30.
- In its dismantled condition the garment may be laid out perfectly flat and thus is capable of being washed and ironed with a 45 minimum of effort and without requiring any special skill on the part of the laundress. When assembled in its intended form, the garment provides a dress of the combination type, which is attractive in appearance and 50 which is easily put on and taken off. At the same time, cutting and sewing of the garment is reduced to the simplest form whereby waste of material and effort is reduced to a minimum.
- 55 While my invention is specially adapted for children's garments of the bloomer dress type, it may readily be adapted for gar-

ments of other types. In any case, any suitable material or combination of materials may be used in the manufacture of the garment. 60

Various modifications in the specific form shown and described may be made within the scope of the claims without departing from the spirit of my invention. 65

I claim:

1. A garment comprising a continuous section of material folded upon itself to form front and back panels of a dress, means for detachably connecting said front 70 and back with each other, and an undergarment comprising two connected sections, one of which is permanently attached to one of said panels and the other of which is adapted to be detachably connected with the same 75 panel.

2. A garment comprising integral front and rear panels folded upon themselves to form a dress, lateral extensions on said panels arranged to define the sleeves, means 80 for detachably connecting said panels at their side edges, and an undergarment comprising a front section permanently attached to one of said panels and a rear section adapted to be detachably connected 85 with the same panel.

3. A garment comprising integral front and rear panels folded upon themselves to form a dress, lateral extensions on said panels arranged to define the sleeves, means 90 for detachably connecting said panels at their side edges, and bloomers comprising one section permanently connected with one of said panels and another section folded upon said first section and detachably connected 95 with said panel.

4. A garment comprising integral front and rear panels folded upon themselves to form a dress, lateral extensions on said panels arranged to define the sleeves, means 100 for detachably connecting said panels at their side edges, bloomers comprising a front section permanently connected with the inner surface of said front panel at a distance from its free edge, a rear section foldable 105 upon said front section, means for detachably connecting said sections along their opposite edges, and means for detachably connecting said rear section with said front panel.

In testimony whereof I have hereunto set my hand.

AMELIA BAILLIE.
